FIG. I.

Fig. 2.

Fig. 5.

Fig. 3.

A technical diagram of a cylindrical component. The top surface has several features labeled with numbers: '18' at the top, '21' on the right side, '15' on the left side, '16' at the bottom left, and '14' at the bottom center. The cylindrical body has a label '19' at the bottom right.

UNITED STATES PATENT OFFICE.

FRANK J. LEWIS, OF BUFFALO, NEW YORK.

PADLOCK.

1,005,852.

Specification of Letters Patent. Patented Oct. 17, 1911.

Application filed March 28, 1911. Serial No. 617,391.

To all whom it may concern:

Be it known that I, FRANK J. LEWIS, a citizen of the United States, residing at Buffalo, in the county of Erie and State of New York, have invented certain new and useful Improvements in Padlocks, of which the following is a specification.

The present invention comprehends certain new and useful improvements in padlocks, and the object of the invention is to provide an improved device of this character which is quite reliable and efficient in operation and which is particularly simple, durable and inexpensive in construction.

Another object of the invention is to provide a padlock consisting of a barrel formed with an opening in one side, a spring-actuated latch bolt mounted within the barrel and movable across the opening, and a shackle pivoted at one end to the barrel and having its free end adapted to be inserted through the opening in the barrel to be automatically engaged with the latch bolt.

A further object of the invention is to provide a padlock of this character in which the barrel is open at one end to permit the insertion of a tubular key that is engaged with the threaded end of the latch bolt to retract the bolt against the force of its actuating spring and thus release the shackle.

With these and other objects in view, as will more fully appear as the description proceeds, the invention consists of certain constructions, arrangements and combinations of the parts that I shall hereinafter fully describe and claim.

For a full understanding of the invention, reference is to be had to the following description and accompanying drawing, in

40 which:

Figure 1 is a perspective view showing my improved padlock and the key therefor, in juxtaposition; Fig. 2 is a longitudinal section of the padlock with the shackle locked in closed position and with the key inserted in the bore to engage the latch bolt; Fig. 3 is a transverse section on the line 3—3 of Fig. 2; Fig. 4 is a perspective view of the latch bolt detached; and Fig. 5 is a longitudinal section showing another embodiment of the invention wherein means are provided for normally retaining the latch bolt against retraction.

Corresponding and like parts are referred to in the following description and indicated in all the views of the accompanying drawing by the same reference characters:

My improved padlock includes a body portion or casing 1 that is in the form of a barrel of any suitable size, the bore 2 of the barrel being open at one end and being permanently closed at its other end in any approved manner, as by means of a screw plug 3. The barrel is formed about midway between its ends with an interior annular shoulder 4, which faces toward the closed end of the bore, the portion of the bore between the shoulder and said closed end being thus of greater diameter than the remainder of the bore. An opening 5 is formed in one side of the barrel and leads into the larger portion of the bore at a point in close proximity to the inner end of the plug 3.

The shackle 6 of the padlock is mounted on the exterior of the barrel and is of approximately the usual form, that is, substantially U-shaped. One end of the shackle is pivoted between a pair of spaced ears 7 that outstand from the periphery of the barrel in proximity to the open end thereof and in longitudinal alignment with the aforesaid opening 5. In the present instance these ears are formed by the outturned extremities of a metal band 8 that is fitted rigidly around the barrel. However it is to be understood that I do not limit myself to this particular construction, but if desired, the ears may be formed integral with the barrel. The free end of the shackle is reduced to provide a tongue 9 and stop shoulders 10 disposed on opposite sides of the base of the tongue, the tongue having a beveled terminal edge 11 and being formed above said edge with an aperture 12. By turning the shackle about its pivot the tongue may be inserted through the opening 5 so as to project into the interior of the barrel. The function of the shoulders 10 is to bear against the periphery of the barrel to limit the inward movement of the tongue. A coil spring 13 is seated on the periphery of the barrel between the ears 7 and exerts its force on the pivoted end of the shackle at a point on one side of the pivot in order to normally withdraw the

tongue from the opening 5 and to support the same in spaced relation to the periphery of the barrel so that the shackle may be readily engaged with the object to be locked.

5 The latch mechanism within the barrel consists of a bolt 14 which is slidably mounted in the bore 2 and which is formed at one end with a substantially cylindrical head or follower 15 fitting the inner or larger portion of the bore. The bolt is held against turning movement within the barrel in any suitable manner, as for instance, by a lug 16 operating in a longitudinal groove 17 in 10 the wall of the bore. A locking projection or tooth 18 is disposed eccentrically on the end face of the head 15 and is arranged at the side of the barrel adjacent to the opening 5. The end of the latch bolt remote 15 from the head is threaded, as indicated at 19, and is received in the smaller portion of the bore and terminates short of the open end thereof, whereby to be entirely held within the barrel and to be substantially 20 non-accessible. Coiled about the intermediate portion of the latch bolt is an expansion spring 20 which is confined between the shoulder 4 and the head 15 and which serves to shoot the latch bolt toward the closed end 25 of the barrel to hold the locking projection 18 against the inner end of the plug 3 and across the opening 5. It is to be noted that the face of the locking projection which is exposed through the opening 5 is beveled as indicated at 21.

In practice, the shackle is turned about its pivot against the force of the spring 13 so as to insert the tongue in the opening 5 and to cause the same to bear against the locking 40 projection 18. The beveled edge 11 is thus brought into engagement with the beveled face 21 and co-acts therewith to shift the latch bolt longitudinally against the force of the spring 20 to afford clearance for the 45 tongue 8 and permit the same to be thrust into the barrel until the shoulders 10 are brought to bear against the periphery of the barrel. In this position the aperture 12 is disposed in longitudinal alignment with 50 the locking projection 18. The spring 20 returns the latch bolt to its normal position and seats the locking projection in the aperture 12, whereby to automatically lock the shackle in closed position.

55 In order to release the shackle there is provided a key 22 which has an interiorly threaded tubular shank 23 and is formed with an annular shoulder 24 at the outer end of the shank. The shank is inserted 60 through the open end of the bore 2 and is turned therein in the proper direction to engage its interior threads with the threaded end of the bolt 14. As the shoulder 24 abuts against the adjacent end of the barrel to 65 limit the insertion of the shank into the

bore, the continued rotation of the key after it has been engaged with the latch bolt, serves to retract the latch bolt against the force of the spring 20, thus unlocking the shackle and permitting the spring 13 to 70 restore the shackle to open position.

It is to be understood that the stems and keys of padlocks may be slightly changed or modified, if desired, so that each key can operate but one lock.

In another embodiment of the invention, illustrated in Fig. 5, means are provided for retaining the latch bolt against retractile movement, said means consisting essentially of a detent 25 that is slidably mounted in 75 a transverse opening 26 in the barrel. This opening is preferably located in the side of the barrel adjacent to the shackle, and communicates with the bore 2 at a point between the open end of the bore and the shoulder 4. The outer end of the opening is permanently closed through the instrumentality of a screw-plug 27 engaged therein. A spring 28 is interposed between the plug and the detent and tends to shoot the inner end of the latter beyond the inner end of the opening 26 and into a notch 29. The notch is formed in the periphery of the reduced threaded end 19 of the latch bolt and is suitably arranged so that it is brought 80 into registry with the opening 26 when the latch bolt is advanced to its normal or operative position by the spring 20. When seated in the notch, the detent serves to positively prevent the latch bolt from being retracted by engaging an instrument other than the key 22, with the threaded end 19. In this instance the tubular shank 23 of the key has a beveled extremity 30 and is of 85 sufficient length to extend inwardly in the bore 2 past the opening 26. When the key is turned into engagement with the threaded extremity of the latch bolt the beveled end 30 is brought to bear against a beveled face 31 of the detent, whereby to press the 90 detent from the notch 29 and into the opening 26 against the force of the spring 28. This releases the latch bolt so that the continued turning movement of the key will 95 retract the bolt in the manner hereinbefore described. By reversing the movement of the key the latch bolt is, of course, returned to its normal position and the detent 25 is 100 permitted to reengage the notch 29.

110 What I claim is:

1. A padlock including a casing having a cylindrical chamber formed in its side wall with a longitudinal groove, the casing being provided with an opening leading into the chamber at a point on the opposite side 115 thereof from the groove, a shackle having its free end apertured and adapted to be inserted through said opening into the chamber, and a locking member having a cylindrical portion mounted to reciprocate with- 120

- in the chamber, the locking member being formed at one side with a longitudinal projection adapted to pass through the aperture in the shackle, said locking member being provided at its opposite side with an outstanding peripheral lug operating in the longitudinal groove to guide the locking member in its movement and to hold the member against rotation.
- 10 2. A padlock including a casing, a latch bolt movably mounted in the casing, means carried by one of said parts and engaging the other part to hold the latch bolt against movement in the casing, a tubular key mov-
- 15 able telescopically into engagement with the latch bolt to shift the same in the casing, and means operated by said telescopic movement of the key, to retract the holding means to an inoperative position.
- 20 3. A padlock including a casing, a latch bolt movably mounted in the casing and having a screw-threaded portion, means en-

gaging the threaded portion of the latch bolt to hold the bolt against movement, and means adapted to be turned into engagement with said threaded portion for forcing the holding means out of engagement therewith.

4. A padlock including a casing, a latch bolt movably mounted in the casing and having a screw-threaded end portion, means for engaging the screw-threaded portion of the bolt to hold the bolt against movement, and a key internally screw-threaded to engage the threaded end portion of the bolt, the key having a beveled extremity adapted to impinge against the holding means to disengage said means from the bolt.

In testimony whereof, I affix my signature in presence of two witnesses.
